UNITED STATES PATENT OFFICE.

ABRAHAM PIASER AND HARRY COHN, OF NEW YORK, N. Y.

WIRE-FRAME MACHINE.

No. 927,163.

Specification of Letters Patent.

Patented July 6, 1909.

Application filed March 27, 1908. Serial No. 423,516.

To all whom it may concern:

Be it known that we, ABRAHAM PIASER and HARRY COHN, both citizens of the United States, and residents of the city of New York, borough of the Bronx, in the county and State of New York, have invented a new and Improved Wire-Frame Machine, of which the following is a full, clear, and exact description.

10 This invention relates to wire frame machines, and more particularly to machines for forming wire hat frames and the like, and each having a plurality of arms carrying wire holders which are adjustable longitudinally of the arms and transversely thereof, and which can be clamped securely in a plurality of positions upon the arms, the latter being pivoted and being simultaneously operable to release a wire frame formed upon 20 the holders.

An object of the invention is to provide a simple, strong and durable wire frame machine which is capable of a plurality of adjustments to permit frames of widely differing forms to be fashioned thereon, and which can be operated to release a frame after the latter is formed, without distorting or altering the form of the frame.

A still further object of the invention is to 30 provide a wire frame machine which is comparatively inexpensive to manufacture, in which wire holders of different forms can be employed, and in which the wire holders are capable of a great range of adjustment and 35 can be held securely in any adjustment, so that there is no danger of their slipping while a frame is being formed.

The invention consists in the construction and combination of parts to be more fully 40 described hereinafter and particularly set forth in the claims.

Reference is to be had to the accompanying drawings forming a part of this specification, in which similar characters of reference 45 indicate corresponding parts in all the views, and in which—

Figure 1 is a transverse section of the machine on the line 1—1 of Fig. 2; Fig. 2 is a transverse section on the line 2—2 of Fig. 1; 50 Fig. 3 is a side elevation showing one of the wire holders; Fig. 4 is an enlarged perspective view of one of the carriers or clamping members for the wire holders; Fig. 5 is a side elevation showing a wire holder of modified

form; and Fig. 6 is an enlarged transverse section showing means of modified form for securing the wire holders upon the arms.

Before proceeding to a more detailed explanation of our invention, it should be clearly understood that while the same is particularly useful for forming wire hat frames, it can also be advantageously employed for forming other frames of wire or the like. In this art, it is customary to employ a plurality of wire holders upon which the wire from which the frame is fashioned, is wound and held while being formed into the frame. The wire holders are adjustable so that frames of different forms can be fashioned thereupon. Our invention provides means for mounting the wire holders so that they are capable of a great many adjustments, and at the same time, when adjusted can be firmly clamped in position and held against casual displacement. Furthermore, in our machine the wire holders are simultaneously movable to release the frame after the latter has been formed, without the danger of bending or distorting any part of it.

Referring more particularly to the drawings, we provide a base 10 which may be mounted upon a table or other support by means of screws 11 or in any other convenient manner. The base 10 has a substantially central upright post 12, upon which is rotatably mounted a standard 13 having the lower portion hollow to receive the post 12 and to form a bearing therefor. At the upper end, the standard 13 is formed into a hollow outwardly extended head 14, having a rim 15 consisting of straight sections 16 angularly disposed with respect to one another. Each of the sections 16 has a recess 17.

Within the head 14 is a hub rod 18 slidably extending into a bore 19 of the standard and having a crown 20 having outward peripheral extensions 21. Each of the latter has a pivot pin 22. A top 23 conforming in shape to that of the head 14 has a rim 24 provided with recesses 25 each of which is adapted to register with a recess 17, and forming with the latter, slots through which the arms 26 extend. The latter are pivoted upon suitable pins 27 journaled in bearings formed between the rim 15 and the rim 24. The inner ends of the arms 26 are pivotally mounted by means of suitable open-

ings, upon the pins 22 of the crown 20. The latter has pivoted thereto a link 28 which is controlled by a lever 29 pivoted in a slot 30 of the head and having a handle 31 by means 5 of which it can be manually operated. The lever 29 serves to raise or lower the hub rod 18 and its crown, to swing the arms upwardly and inwardly for a purpose which will appear more clearly hereinafter. The 10 top 23 is mounted upon the head by means of screws 32 or in any other convenient manner.

Upon each of the arms 26 is slidably mounted one or more blocks 33 having a 15 suitable opening for the purpose, and provided with threaded stems 34. Each of the blocks has a sleeve 35 mounted thereon and has a set screw 36 adapted to engage a longitudinal groove 37 of the arm to secure the 20 block 33 firmly upon the arm at any desired point of the latter. Upon each stem 34 is located a plurality of wire holder carriers 38 consisting preferably of disks or plates having substantially central openings 39 to receive the stem, and provided with a segmental undercut recess or groove 40 in one face.

The wire holders 41 are preferably in the 30 form of elongated rods having at one end hooks to hold the wire, or notches 42 for a like purpose. It will be understood that the holders 41 may be bent or curved into any suitable form and may be fashioned to suit individual preference or special conditions. 35 The holders are formed to fit slidably into the grooves 40 and to extend slightly beyond the adjacent faces of the carriers 38. Each of the stems 34 has a nut 43 which serves to jam the parts together and to lock the carriers as well as the holders in any desired 40 position. It will be seen that by adjusting the nuts 43, the carriers 38 themselves serve to secure the holders in position, as each of the latter extends slightly beyond its carrier, 45 and at the same time the carrier adjacent to the sleeve 35 jams the latter against the arm 26 thus serving to hold the block upon the arm.

In Fig. 5 is shown a wire holder of modified 50 form which has an extended portion 44 provided with openings 45 each of which is adapted to receive directly, a stem 34 so that the carriers 38 can be dispensed with. In the modified detail shown in Fig. 6 a block 55 46 is shown mounted upon an arm 26 and having on its stem 34 a loose U-shaped bracket 47, the arms 48 of which have the extremities curved to seat upon the arm 26, and which is jammed against the latter to 60 lock the parts in position when the nut 43 upon the stem is tightened. It will be understood that the nut 43 may be of any suitable form, for example, an ordinary nut, or a butterfly or thumb nut.

65 The holders 41 have extended portions 49,

to prevent the holders from sliding through the grooves 40 and falling from the arms when the nuts are loosened to adjust them.

The arms are adjusted in accordance with the design of the frame to be formed, and the 70 wire A from which the frame is fashioned is then wound upon the holders engaging the grooves 42, as shown most clearly in Fig. 2. When the frame is completed and it is desired to remove it from the machine, the 75 lever 29 is raised so that the rod 18 is moved downward, carrying with it the crown, and swinging the arms 26 upwardly and inwardly as indicated in Fig. 2. The simultaneous movement of the arms releases the holders 80 from the wire and permits the frame to be removed from the machine, without distortion or other injury.

Having thus described our invention, we claim as new and desire to secure by Letters 85 Patent:—

1. In a device of the class described, a rotatable standard having a hollow head, a rod movable longitudinally of said standard and having a crown within said head, a top 90 upon said head, said head and said top forming slots therebetween, arms pivoted in said slots and having adjacent ends secured to said crown, a lever controlling said rod, and a plurality of adjustable wire holders mounted 95 upon each of said arms.

2. In a device of the class described, a rotatable standard having a laterally extended hollow head, a rod guidingly mounted within said standard and movable longitudinally 100 thereof, said rod having a laterally extended crown within said head, a top upon said head, said top and said head having cut away parts forming openings, arms pivotally mounted in said openings and having 105 slots at the inner ends, said head having pins adapted to engage movably in said slots, said head having a further opening in the side thereof, a lever pivoted in said further opening, a link connecting said rod and 110 said lever, and a plurality of adjustable wire holders mounted upon each of said arms.

3. In a device of the class described, an elongated member, a second member slidably carried by said first member, one of said members having a groove extending longitudinally thereof, the other of said members having a projection slidably engaging said groove, a plurality of carriers loosely mounted upon said second member, wire holders, 115 each arranged between two adjacent carriers, and means for clamping said carriers together, whereby said members are caused to bind.

4. In a device of the class described, an 125 arm having a groove, a member movable on said arm and having a stud engaging said groove, a second member loosely carried by said first member and slidably engaging said arm, carriers loosely mounted upon said 130

first member, and means for clamping said carriers together, whereby said members are caused to bind upon said arm, said carriers being adapted to secure wire holders therebetween.

5. In a device of the class described, an arm, a block having an opening whereby the same is slidably mounted upon said arm, a sleeve loosely arranged upon said block and 10 having an opening movably receiving said arm, said block having a threaded stem, carriers loosely mounted upon said stem, wire holders between said carriers, and a nut upon said stem for forcing said carriers toward said sleeve to cause said sleeve and said block to bind upon said arm.

6. In a device of the class described, an arm, a block slidably mounted upon said arm and having a sleeve engaging said arm, 20 said block having a stem, carriers movably mounted upon said stem and each having a groove, wire holders mounted in said grooves, and adjustable means upon said stem for forcing said carriers toward said sleeve, said 25 wire holders having a thickness greater than the depth of said grooves.

7. In a device of the class described, an adjustable arm, a block slidably mounted upon said arm and having means for holding 30 it in a plurality of positions thereupon, a sleeve loosely carried by said block and engaging said arm, said block having a threaded stem, plates loosely mounted upon said

stem, a nut arranged upon said stem and adapted to force said plates against said 35 sleeve whereby said sleeve is jammed against said arm to lock said block in position thereupon, said plates having undercut grooves, and wire holders each formed to be slidably mounted in one of said grooves, said wire 40 holders being of a thickness greater than the depth of said groove.

8. In a device of the class described, a plurality of pivoted arms, members adjustably mounted upon said arms, a plurality of carriers mounted upon each of said members and each having an under-cut groove at one side, said grooves being on corresponding sides of said carriers, wire holders of angular section and formed to fit said grooves and 50 each arranged between two adjacent carriers in said grooves, and means for simultaneously clamping said carriers of each of said members and securing each member upon its arm, said arms having grooves, said 55 members having projections slidably engaging in said grooves.

In testimony whereof we have signed our names to this specification in the presence of two subscribing witnesses.
